UNITED STATES PATENT OFFICE.

OLCOTT JACKSON, OF BROOKLYN, NEW YORK, ASSIGNOR TO HECLA IRON WORKS, OF BROOKLYN, NEW YORK, A CORPORATION OF NEW YORK.

GRATING AND METHOD OF CONSTRUCTING SAME.

1,356,151.

Specification of Letters Patent. Patented Oct. 19, 1920.

Application filed February 10, 1920. Serial No. 357,580.

To all whom it may concern:

Be it known that I, OLCOTT JACKSON, a citizen of the United States, and a resident of Brooklyn, in the county of Kings and 5 State of New York, have invented certain new and useful Improvements in Gratings and Methods of Constructing the Same, of which the following is a specification.

My invention relates to steel or other metallic gratings and to the method of constructing the same and has for its object 10 the production of a grating of simplicity of construction, of strength and of low cost to manufacture, the members of which may 15 be readily assembled and easily and accurately joined together.

It has heretofore been customary to construct gratings by providing the members thereof with holes at their points of meeting or intersection and passing rivets through the holes and joining the members by an ordinary riveting operation. This necessitates turning the members on their 20 sides and holding them in this position with the holes in vertical alinement in order to perform the riveting operation which is inconvenient and frequently requires the mere adding together and riveting of but one or two members at a time, or in other words, a 25 gradual building up of the structure, which is time-consuming and inconvenient. Furthermore this method is objectionable for the reason that the riveting operation in a great many cases has the effect of stretching or drawing the metal members particularly if the members are sinuous or other 30 than perfectly straight and if the members are of some length the holes or perforations therein at a point remote from any riveting operation will be drawn out of alinement, 35 thereby making difficult or impossible at that remote point a riveting of the members together.

By practising my invention I have found 40 that the objections hereinbefore noted have been obviated, that the members may be fastened together to produce the finished or completed grating more easily and expeditiously than by riveting them together and 45 that the finished grating possesses as much strength and rigidity as if its members had been joined by riveting. Furthermore my invention permits a member or members to be removed from the completed structure

and replaced should they become damaged 55 or broken.

A practical embodiment of the invention is illustrated in the accompanying drawings in which:

Figure 1 is a plan view of my improved 60 grating.

Fig. 2 is a vertical cross-section on the line 2-2 of Fig. 1.

Fig. 3 is a front elevation of one of the 65 sinuous members of the grating.

Fig. 4 is a perspective view of the clip 70 for joining the members together.

Referring in detail to the several figures 75 of the drawing:

1 indicates the straight longitudinal metallic members and 2 the sinuous metallic members intermediate the longitudinal members of a grating which are joined or connected at their crests 3 to the straight longitudinal members to produce the finished 80 grating. If the old riveting operation were employed for joining the members together they would be provided with holes at their points of meeting or intersection, for instance at the point A, 85 where the crests of the sinuous members meet or engage the longitudinal members, then turning the members over with their sides parallel to the ground, passing rivets through the holes and riveting the members 90 together three at a time at successive points. These operations would be continued by a building up process, that is by the addition to and riveting to the structure of additional members until it has reached or attained 95 the desired size. When, however, the members were riveted together at the point A, it would be found that the sinuous members which are riveted to the longitudinal member at that point would be drawn or 100 stretched so that when the point B, for instance, were reached for the riveting operation, the holes with which the members are provided for riveting at that point would be apt to be drawn out of alinement, thereby 105 precluding the riveting operation or making it impracticable at the point B. According to my invention I provide the members at their meeting or intersecting points with holes 4, preferably rectangular-shaped, and of a size permitting them to snugly receive flat rectangular-shaped locking clips 5. All the parts of the grating, that is, the

sinuous members 2 and the longitudinal members 1 that form the complete structure of the required size are then assembled on their edges on a table or other support 5 in substantially the same position they occupy as in the finished product and the locking clips 5 are slipped through the holes 4 of the sinuous members and the longitudinal members with the ends 5' thereof which 10 form flanges projecting outwardly as shown at the right of Fig. 2, which clips prevent drawing or stretching of the members at any point. Said ends or flanges 5' are then forcibly bent downwardly into locking engagement 15 with the sides of the crests 3 of the sinuous members 2 by means of a forked tool 6 having arms 7 for engaging said ends or flanges 5'. This effects a locking of the members of the grating together as is obvious 20 and the locking or joining operation may be easily and expeditiously accomplished. Also if it is desired to replace any of the members of the grating, this may be accomplished by unlocking the clip joining that 25 member to the other members by turning the flanges thereof upwardly, removing the clip and joining the new member to the other members in the manner previously described.

What I claim as my invention is:—

- 30 1. A metallic grating comprising longitudinal members and sinuous members intermediate said longitudinal members with the crests of the sinuous members engaging the longitudinal members, said longitudinal and sinuous members being provided with holes 35 in alinement at their points of meeting and locking clips passing through said holes and provided with flanges bent over against the flat sides of the sinuous members to hold 40 the longitudinal and sinuous members in locking engagement.

2. The herein described method of constructing a metallic grating comprising longitudinal members and sinuous members consisting in providing the members with 45 holes, assembling the members on their edges with the holes in register, passing locking clips through said holes and bending the ends of the locking clips over into engagement with the sides of the members to lock 50 them against relative movement.

3. The herein described method of constructing a metallic grating comprising longitudinal members and sinuous members consisting in providing the sinuous 55 members with holes at their crests and the longitudinal members with holes adapted to register with the holes in the sinuous members, assembling the parts on their edges with the sinuous members intermediate the 60 longitudinal members and engaging the same and with the holes in the members in register, passing clips through said holes and bending over the ends of said clips into locking engagement with the sides of the 65 sinuous members.

4. The herein described method of constructing a metallic grating consisting in providing the members thereof which form the complete structure of the required size 70 with holes, assembling the members on their edges with the holes in register, passing locking clips through said holes and bending the ends of the locking clips over into engagement with the sides of the members. 75

Signed at Brooklyn, in the county of Kings and State of New York this 4th day of February, A. D. 1920.

OLCOTT JACKSON.
